DESIGN FOR A JEWEL MOUNTING

Otto J. Somers, New York, N. Y.

Application July 22, 1939, Serial No. 86,178

Term of patent 7 years

To all whom it may concern:

Be it known that I, Otto J. Somers, a citizen of the United States, residing at New York city, in the county of New York and State of New York, have invented a new, original, and ornamental Design for a Jewel Mounting, of which the following is a specification, reference being had to the accompanying drawing, forming a part thereof.

Fig. 1 is a face view of the jewel mounting showing my new design;

Fig. 2 is a side view.

I claim:

The ornamental design for a jewel mounting, substantially as shown.

OTTO J. SOMERS.
